UNITED STATES PATENT OFFICE.

WILLIAM H. RICKS, JR., AND WALTER MEISENBACH, OF HYSHAM, MONTANA.

PAST AND FUTURE REFERENCE-CALENDAR.

1,330,281.

Specification of Letters Patent. Patented Feb. 10, 1920.

Application filed August 9, 1919. Serial No. 316,397.

To all whom it may concern:

Be it known that we, WILLIAM H. RICKS, Jr., and WALTER MEISENBACH, citizens of the United States of America, residing at 5 Hysham, in the county of Rosebud and State of Montana, have invented certain new and useful Improvements in Past and Future Reference-Calendars, of which the following is a specification.

10 This invention relates to past and future reference calendars and it has for its object the provision of a simple and inexpensive device of the character referred to by means of which it will be possible to readily determine what day of the week any particular day fell upon throughout the past or will fall upon throughout the future either under the old style or Julian calendar, or under the new style or Gregorian calendar. 15 Further objects and advantages of the invention will be set forth in the detailed description which now follows.

The figure shown in the accompanying drawing is an elevation of a calendar constructed and arranged in accordance with the invention.

Referring to the drawing 5 designates a card constituting the body of the calendar and 6 and 7 designate swinging sections 20 pivotally connected to the card 5 by means of eyelets 8 and 9, and having their confronting ends curved at 10 and 11 upon arcs of circles struck from the centers of the eyelets 8 and 9. The swingingly mounted 25 or pivoted section 6 bears matter adapting this section to co-act with the remainder of the calendar to determine dates under the "old style" or Julian calendar, while the pivoted section 7 bears like matter adapting 30 that section to co-act with the remainder of the calendar to determine the date under the "new style" or Gregorian calendar. In each case the section carries a plurality of arcuate columns of figures 12 which in conjunction with radial rows 13 constitute 35 spaces 14 within which are printed numerals from 1 to 100 indicative of the years of the century. Each pivoted section 6 or 7 also carries one or more hands or pointers 15, the 40 position to which said hand is to be set being determined by symbols 16 set opposite and alined with figures 17 indicative of the several centuries.

The body of the calendar comprises a plurality of arcuate columns 18 intersected by lateral rows 19 to constitute spaces which

receive the names of the months of the year as indicated at 20 for example. The columns 18 are subdivided by flaring lines 21 to form a plurality of smaller columns 22 60 in which appear the names of the days of the week as indicated at 23. These columns 22 are further divided laterally to form spaces 24 for the reception of numerals indicative of the days of the month. 65

In addition to the foregoing, arcuate columns 25 and 26 are formed adjacent the curved front edges of the sections 6 and 7, and concentric therewith, in which appear symbols 27 corresponding to the symbols 16, 70 and with which the hands 15 are adapted to co-act.

The method of use of the device is as follows:—

Assuming that it is desired to find what 75 day of the week the 31st day of May 1919, will fall upon, reference is made to the century table of the Gregorian calendar upon the pivoted section 7 and it will be found that the symbol C, among the symbols 16 appears opposite the years 1901 80 to 2000. This pivoted section is then swung to such a position as to bring the hand 15 opposite the symbol C in column 26, this will bring the numeral 19, indicative 85 of the year 1919 in alinement with that lateral row containing the names of the months, that we have specially designated X for the purpose of this explanation. Following this row across it will be found that 90 the month of May occurs in the third column from the right and by referring to the monthly calendar at the top of this column it will be observed that the 31st day, therefore, falls on Saturday. 95

In addition to the hands 15 we have provided upon the Gregorian calendar a symbol consisting of the figure 100 and specially designated by the reference character Z that is to be used in lieu of the hand 15 for determining the proper positioning of the section 7 in finding days occurring in leap years, and it will be observed that the names of certain of the months in the column 18 and throughout certain of the rows 105 19 appear in heavier faced type than is the case with like names appearing in the other rows and this is for the purpose of indicating leap years.

It will be noted that hands 15 appear at 110 both the upper and lower portions of the sections 6 and 7, and either of these hands

may be used according to whether the year of the century is found adjacent to top of the section or adjacent to the bottom thereof. We prefer to indicate the leap years in the 5 Gregorian calendar with some distinctive mark, such for example as the star shown at 28.

It is to be understood that the invention is not limited to the precise construction set 10 forth nor to the specific arrangement shown, for we contemplate printing the body of the calendar in varying colors if desired, and we contemplate printing upon the body of the card 5 whatever suitable explanation 15 may be desired concerning the use of the calendar. However these are manifestly changes coming merely within the skill of the printer and constituting no departure from the principles involved.

20 Having described our invention what we claim is—

In a perpetual calendar a body portion having a plurality of arcuate columns bearing the names of the months of the year 25 arranged in rows transversely of all of said columns and a monthly calendar relating to each of said columns, a member pivoted to said body portion to swing upon the arc

of a circle over the face thereof, said member having its free edge formed concentrically with the pivot point and the outermost of said arcuate columns being concentric with the said edge, said member and said body portion having coöperating indicia to indicate where the movable member is to 30 be set with respect to the body portion, said member having transverse rows of figures relating to the years of the century, the arrangement of said figures and the arrangement of the names of the months being such, 35 that when the movable member is set with relation to the body portion in accordance with the indicia, the row of figures relating to the years of the century in which the year concerned appears, will aline with that row 40 upon the body portion bearing the name of the month concerned, in that column that is related to the monthly calendar adapted to 45 give the information sought.

In testimony whereof we affix our signatures in the presence of two witnesses.

WILLIAM H. RICKS, JR.
WALTER MEISENBACH.
